UNITED STATES PATENT OFFICE.

FREDERICK M. DAYTON, OF NEW YORK, N. Y.

TOY-BALLOON VALVE.

1,251,758.

Specification of Letters Patent.

Patented Jan. 1, 1918.

Application filed February 24, 1917. Serial No. 150,795.

To all whom it may concern:

Be it known that I, FREDERICK M. DAYTON, a citizen of the United States, residing at 39 W. 32 St., New York, in the county of New York and State of New York, have invented a new and useful Toy-Balloon Valve, of which the following is a specification.

The present invention relates to valves for toy balloons, and aims to provide a novel and improved check valve for preventing the escape of air or gas when the balloon is inflated.

It is the object of the invention to provide a toy balloon valve of extremely simple and compact construction, which can be inexpensively manufactured, and which is thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view of one form of valve.

Fig. 2 is a diametrical section thereof illustrating the valve disk seated.

Fig. 3 is a diametrical section of a modification as applied to the neck of the balloon.

In carrying out the invention, there is provided a disk 1 provided with a central aperture 2 and having a marginal flange or rim 3 extending toward one side for housing the valve disk or member 4. This valve disk is composed of a sheet of soft pliant rubber or equivalent material and is of slightly smaller diameter than the flange or rim 3.

The edge of the flange or rim 3 is provided with inturned ears 5, three of them being illustrated, although any suitable number can be employed. A stiff disk 8 of metal, cardboard or the like, is disposed loosely within the flange or rim 3 between the disk 4 and ears 5. These ears 5 act as stops to limit the movement of the disk 8 away from the seat provided by the disk 1 surrounding the aperture 2 and the disk 8 acts as a stop

to limit the movement of the disk 4. The disk 1 can be provided with an annular cor-

rugation 6 surrounding the aperture 2 and projecting in the same direction as the flange 3, so that the valve disk 4 in being pressed against the corrugation 6 will provide a gas tight fit, to avoid leakage. The disk 1 with its flange 3 and ears 5 can be readily stamped from sheet metal or other suitable stock, and the construction is exceedingly simple and inexpensive. The flange 3 not only accommodates the valve 4, but also enables the device to be applied to the neck or nipple of the balloon. The device is so applied that when the balloon is being inflated, the disks 4 and 8 are blown bodily away from the aperture 2 against the ears 5, thereby permitting of the passage of air or gas, but as soon as the inflation of the balloon is stopped, the reverse flow of air or gas, due to the tendency of the balloon to deflate itself, will be prevented because of the fact that the disk 4 will be blown against the seat or disk 1 with the disk 8, thereby closing the aperture 2. The valve disk 4 is normally flat, but being composed of soft pliant rubber will fit tightly against the disk 1 and bulge within the aperture 2 for preventing leakage. The disk 8 prevents the excessive bulging of the disk 4. The disks 4 and 8 are of larger diameter than the corrugation 6, whereby when the disk 4 seats against the corrugation, the disk 8 in being pressed against the disk 4, will bear against that portion thereof which bears against the corrugation 6, thus providing a tight closure. Furthermore, the disk 8 prevents the disk 4 from being bulged outwardly or forced between the ears 5.

The structure shown in Fig. 3 is somewhat similar to that shown in Figs. 1 and 2, with the exception that the ears 5 are offset to further limit the movement of the valve disk 4 away from the seat.

The rim or flange 3 is concaved transversely or is in the form of an annular instruck corrugation providing an outer annular groove for receiving and holding with an airtight fit the bead 9 on the end of the balloon neck 7, said bead contracting and seating in the groove.

The present valve is not only useful for toy balloons, but can also be used for retaining air in various inflatable devices, such as foot ball bladders, tires, and the like.

Having thus described the invention, what is claimed as new is:

1. A valve embodying a seat member hav-

ing an aperture and rim, a pliant valve member within said rim seatable against the seat member to close said aperture, said rim having inturned means spaced from said seat member for limiting the bodily movement of the valve member away from the seat member, and said rim being concaved transversely between said seat member and means for the reception of an elastic member within 5 which the valve is inserted.

10. 2. A valve embodying a sheet metal disk having an aperture and a marginal flange extending to one side, a pliant valve disk movable within said flange and seatable 15 against the aforesaid disk to close said aperture, said flange having inturned ears spaced from said valve disk for limiting the bodily movement of the valve disk away from the first mentioned disk, and said 20 flange being concaved transversely between said disk and ears for the reception of an elastic member within which the valve is inserted.

3. A valve embodying a sheet metal disk 25 having a central aperture, a corrugation surrounding said aperture, and a marginal flange, a pliant valve disk movable within

said flange and seatable against the aforesaid disk and its corrugation to close said aperture, and a stiff disk within said flange 30 to bear against the valve disk, the edge of said flange having inturned ears for limiting the bodily movement of the valve and stiff disks away from the first mentioned disk, the valve and stiff disks being of 35 greater diameter than the corrugation.

4. A valve embodying a seat member having an aperture and a rim, a pliant valve member within said rim seatable against the seat member to close said aperture, and a 40 stiff member within the rim seatable against the valve member to press it against the seat member and prevent excessive bulging thereof, said rim having inturned means spaced from the seat member for limiting the bodily movement of the stiff member away from the seat member.

In testimony that I claim the foregoing as my own, I have hereto affixed my signature in the presence of two witnesses.

FREDERICK M. DAYTON.
